APPARATUS FOR THE DESIGNING OF
BUILDINGS

Thomas H. Reeves, Birmingham, Ala.

Application November 5, 1931, Serial No. 573,134

3 Claims. (CL. 35—16)

My invention relates to a new and improved apparatus for simplifying and perfecting the designing of buildings, and, while not specifically limited thereto, is principally concerned with 5 perfecting a means for the designing of residences or homes whereby a prospective builder may be enabled to visualize the projected building in advance of its erection and to adjust the design to fit his immediate and particular needs.

10 Heretofore, all buildings and particularly residences have been built in accordance with plans prepared by architects and submitted to the prospective builder. Very few people are skilled in the reading of blue prints and even the few that 15 are so skilled can hardly visualize and apprehend the exact result in designing or arrangement which will be obtained in the finished building. As a result, nearly all residence builders are subjected to expensive and troublesome changes in 20 plans and specifications and yet, even while some changes can still be made within the limits of reasonable expense, it is true that in a majority of times it is only after the house is built and beyond the possibility of change that the disappointing features in the design and arrangement 25 become apparent. Generally this occurs when the home builder moves in and seeks to arrange his furniture in the various rooms. Then it is found that one room is too large, another too 30 small, that the openings, both window and door, are ineptly placed so that the furniture must be disposed where it is not convenient or sightly, or part thereof must be entirely eliminated.

I have conceived that, if any apparatus could be 35 devised that would be effective to overcome those difficulties for the ordinary non-technical builder, it must be designed to present the true proportion of the structure to be erected, as it is only with reference to true proportions that the average 40 person can, in a practicable manner, understand the house design and visualize the furniture arrangement. To this end I have conceived the idea of providing a suitable floor space, ample 45 for the laying out thereon in full size of any ordinary house floor plan. To facilitate this laying out, the floor may be marked into foot squares so that reading from the architect's drawing it will be a comparatively simple matter to reproduce 50 in full size on this floor space the outline of the building walls and partitions.

I provide suitable portable dummy wall partitions, made of light material, so that they may be readily set up and which are of substantial height so as to give a fairly accurate conception of the 55 proportions of the rooms which they may be used

to define. My invention contemplates a variety of means which may be used to define the walls and interior subdivisions of the proposed building, so long as thereby I secure in effect a full sized floor plan subdivided by partitioning of only sufficient height to enable the room effect to be correctly visualized.

My invention further contemplates these dummy units in varying lengths and with special units adapted to indicate the position of windows and doors, thereby permitting the openings in a room to be designated.

My invention further contemplates providing light portable full size dummy representations of articles of furniture which may be placed within the confines of the various rooms defined by the dummy partitions and thus convey in true proportion the setting of these articles as it may be desired to place them in the room and thereby to permit the redesigning of the room where necessary to the better accommodate such articles of furniture.

My invention further contemplates providing the dummy partition sections with means to interlock their abutting ends so that they can be quickly set up and will be rigidly held in place during the inspection and rearrangement of the particular floor plan or building design under consideration.

My invention further comprises the novel details of construction for practicing the invention, which will be hereinafter more particularly described and which will be better understood by reference to the accompanying drawings which form a part of this specification, and in which:

Fig. 1 is a plan view of a floor section with a design of a building reproduced thereon by my improved dummy partitions which are shown in plan view with the arrangement of dummy articles of furniture shown in dotted lines.

Fig. 2 is a fragmental view in perspective showing a corner of one of the rooms illustrated in Fig. 1 with dummy articles of furniture arranged therein.

Figs. 3 and 4 are side and end views of a standard dummy wall partition section, the view in elevation being broken away.

Figs. 5 and 6 are corresponding views of a dummy wall section for use adjacent to a door opening.

Figs. 7 and 8 are plan and elevational views of a right angle corner wall section.

Figs. 9 and 10 are similar views of a T-wall section.

Figs. 11 and 12 are similar views of a window section.

Fig. 13 is a plan view of Fig. 11.

Figs. 14 and 15 are plan and elevational views 5 of the dummy elements defining a door opening.

Fig. 16 is a view taken on the line XVI—XVI of Fig. 3 showing the dummy end connections separated.

Fig. 17 is a similar view showing the dummy end 10 sections connected.

Similar reference numerals refer to similar parts throughout the drawings.

In the embodiment of my invention illustrated, I show a floor 20, which may be of any desired 15 material and which is preferably divided by intersecting lines spaced on foot centers, so that it will be easy to measure off distances and to lay out straight lines thereon. It is generally contemplated that such a floor will be provided for 20 the use of customers of the architect, builder or supply house, to the end that by employing the mechanism which will now be described, various floor plans of buildings and particularly of dwellings can be set up on this floor according to their 25 actual dimensions.

The mechanism employed for carrying my invention into effect comprises a series of standard dummy wall partition units 21, one of which is more clearly illustrated in Figs. 3 and 4, and is 30 made up with a substantially wide bottom board 22 shaped along its wide edges to give the effect of a base shoe 23 and having mortised therein the base boards 24, which are rabbeted on their inner faces to receive the light composition or wood 35 wall boards 25 which at their tops are connected to a top board 26.

Each unit is provided with suitable end walls 40 formed by studs 27, one stud having a groove 28 and the other a complementary rib 29. Intermediate studs are used in long wall units. The rib 45 has anchored therein and projecting therefrom eye bolts 30 and the grooves have slots 31 adapted to receive these eye bolts. The top board is provided near each end with a hole 32 adapted to receive a vertical rod 33 which passes down through the eye bolts and interlocks the end sections together as shown more clearly in Fig. 17. These eye bolts are adjustable by being screwed 50 into a threaded opening in an anchor plate 34 connected to the inside of the end wall 27.

The dummy wall sections thus provided are approximately three feet in height, it being important that this height be just sufficient to enable one, viewing an enclosure formed thereby, to obtain 55 a reasonably accurate conception of the proportions of the finished room. It is well known that rooms do not assume their correct proportions to unskilled or inexperienced observers until the partition walls defining them are set up, and 60 it is therefore obvious that some sacrifice of complete presentment of the building design must be waived in the interest of economically producing dummy partition units which will be light enough to be easily handled and small enough to be 65 economically produced. It is thought that approximately three feet or four feet in height will be sufficient for the purposes contemplated and it will be understood that in making up the standard partition units described material which is 70 light is employed. The dummy unit bottom and base is preferably of heavy wood while the body is of light wooden or composition boards.

Without describing in detail the various dummy 75 sections that would be provided, it seems sufficient to say that in Fig. 7, I show a dummy section

differing from Fig. 3 only in providing the angled wall unit 35 and in Fig. 9 is shown a T-shaped unit 36. It will also be understood that the length of the standard units 21 will be varied so that it will be feasible, with reasonable accuracy, to reproduce the exact dimensions of each room being exemplified.

In Figs. 11 and 12, I show what I term a dummy window unit 37 which comprises a lower wall section interlocked with the standard wall units 21 10 and adapted to receive a window unit 38, shaped to slip fit over the top 26 and over the adjacent ends of the units 25 so as to hold this window section standing substantially above the top level 15 of the standard wall sections, whereby to emphasize the location of the window opening.

In Figs. 14 and 15, I show the wall sections 39 for a door opening, these sections having post members 40 and one of these members carrying a hinged door board 41 which is adjustable as to 20 length to suit the door opening and the hinge 42 of which is reversible to the swing of the door and the room into which it opens.

Having before one a floor plan, such as appears in Fig. 1, to practice my invention the 25 standard and special dummy wall unit sections are selected as required and the rooms are laid out starting from any desired point and following the dimensions of the architect's drawings or developing the layout without plans. 30 When the rooms have thus been defined with their window and door openings in position, dummy furniture may also be provided and installed in the various rooms so that their proportions can be understood, the space provided for them 35 relative to the window and door openings checked and modified where necessary, and the whole house thus tested by actual experience until the proper readjustments of partitions and openings are finally agreed upon according to the pleasure 40 and for the greatest convenience of the house builder. Thereupon the architect can readily correct his plans and the erection of the building can proceed with the least probability of alteration and change in plans and therefore with 45 the consequent reduction of building expense.

It will of course be understood that the dummy sections which have been described are those which I have built and by trial have found are suited to the purposes stated, but others may 50 modify this manner of forming the representation of the building walls and partitions without departing from the essential features of my invention for which I seek protection and which are pointed out in the appending claims.

While I have shown my invention in but one form, it will be obvious to those skilled in the art that it is not so limited, but is susceptible of various changes and modifications, without departing from the spirit thereof, and I desire, 60 therefore, that only such limitations shall be placed thereupon as are imposed by the prior art or as are specifically set forth in the appended claims.

What I claim is:—

1. An apparatus for producing, by dummy representation, the wall and partition arrangement of a proposed building, comprising, in combination, a floor ample in size to receive the full size layout of the floor plan to be represented, and a plurality of wall and partition unit sections of partial height adapted to stand upright on said floor and to be assembled thereon to reproduce the walls and partitions in full length but in partial height.

2. As an article of manufacture, a representation of the floor plan of a building layout in full size as to length and comprising a plurality of dummy elements representative of a vertical section of the lower portion of a wall partition, means associated with said elements to represent doors and windows of the building, said sections being readily movable about over their support, and means to interlock the sections in assembled 5 position to correspond to the floor plan of the building, said sections each having sufficient height when assembled to enable the proportions of the proposed dwelling to be apprehended and checked in advance of its permanent erection.
3. In an apparatus for producing, by dummy representation, the wall and partition arrangement of a proposed building, in combination, a floor ample in size to receive a full size layout of the floor plan to be represented and having 5 its surface marked by intersecting lines into squares of unit area, and means representative of but having only part of the height of the walls and partitions of the proposed building which are assembled in upright position on said floor so as to reproduce thereon the arrangement of such building's walls and partitions in full 10 length but only in partial height.

THOMAS H. REEVES.
